AIRPLANE

Oscar D. Payne, Fort Worth, Tex.

Application March 19, 1934, Serial No. 716,343

1 Claim. (Cl. 244—35)

This invention relates to an airplane, and has particular relation to a novel construction of the wing or plane assembly.

An object of the invention is to provide air craft, of the character described, with a novel type of wings or supporting planes having upper and lower plates, preferably of metal and a nest of intervening tubes secured between said upper and lower plates, all firmly secured together to provide a rigid wing construction.

Another object of the invention is to provide in air craft, a wing construction wherein all struts and tie rods, commonly used in the present type of wings, will be eliminated.

15 A further object of the invention is to provide, in air craft, wing construction having tubes, leading fore and aft therethrough, for the passage of air to eliminate the wind resistance of the wings to conduce to smoothness of operation 20 of the plane and to increase the speed of the plane and to increase the lifting power of the wings.

Another object of the invention is to provide, in air craft, a novel type of plane or wing through 25 which the air currents may pass, thus enabling the plane to take off more quickly and to land more smoothly due to the passage of said currents through the tubes of the wings.

With the above and other objects in view, this 30 invention has particular relation to certain novel features of construction, arrangement of parts and use, an example of which is given in this specification and illustrated in the accompanying drawings, wherein:

35 Figure 1 shows a front elevation of an air craft embodying the invention.

Figure 2 shows a cross sectional view taken on the line 2—2 of Figure 1.

Figure 3 shows an enlarged fragmentary front 40 elevation.

Figure 4 shows a plan view, and

Figure 5 shows a cross sectional view taken on the line 5—5 of Figure 4.

In the drawings, the numeral 1 designates the 45 fuselage having the motor 2 and the propeller 3 at the front end thereof, all of which may be of any selected construction. The craft has the usual landing gear 4. The numerals 5, 5 designate the wings of the craft as a whole. Each 50 wing includes the upper and lower plates 6, 7, said plates extending the full length of the wing

and being suitably anchored to the fuselage. The upper and lower plates 6, 7 may be secured together at their outer ends in any preferred manner as by welding.

Between the plates of the wings are the tubes 8 5 nested closely together as more accurately shown in Figures 1 and 3. These tubes extend from the forward to the rear margins of the wings and are disposed parallel to provide air passageways through said wings to decrease the wind re- 10 sistance.

As more clearly shown in Figure 4, the top 15 plates 6 are somewhat narrower than the bottom plates 7, the rear ends of the tubes thus terminating on the upper rear surface of the corresponding wing. The tubes 8 may be suitably anchored together and to the plates as by welding to provide a very strong and rigid wing structure. As the craft is propelled forwardly the air will 20 pass through the tubes 8, thus eliminating the head wind resistance making it possible to take off in a short space of time. The lifting power of the wings will be increased for the reason that the lifting area of the bottom plates 7 will be increased by the lifting area of the tubes 8, thus 25 increasing the vacuum above and in rear of the wings.

The passage of the air currents through the tubes 8 will also conduce to smoothness of operation of the craft which, by reason thereof, will 30 pass more smoothly through cross currents and will also land more smoothly, the currents of air passing through said tubes having a stabilizing effect while flying and landing.

The drawings and description disclose what is 35 now considered to be a preferred form of the invention by way of illustration only, while the broad principle of the invention will be defined by the appended claim.

In an airplane, a wing having an upper plate 40 and a lower plate spaced apart, the upper plate being narrower than the lower plate, a plurality of rows of tubes between said plates and arranged parallel therewith and forming straight air channels leading from the forward margin to the rear 45 margin of the wing, said tubes increasing in length from above downwardly and the rear ends of the tubes terminating in a common plane, the rear margins of said plates also terminating in said common plane.

OSCAR D. PAYNE.
